(57) **CLAIM**

The ornamental design for a wing hand shaped display, as shown and described.

DESCRIPTION

FIG. 1 is a front view of a wing hand shaped display showing the claimed design;

FIG. 2 is a rear view thereof;

FIG. 3 is a right side view thereof;

FIG. 4 is a left side view thereof;

FIG. 5 is a bottom view thereof;

FIG. 6 is a top view thereof;

FIG. 7 is a front view thereof shown in an environment in which the claimed design may be used; the words “LOGOS HERE” indicate where a user might place an ad; and,

FIG. 8 is a rear view thereof.

The broken lines of the words “LOGOS HERE” in FIGS. 7 and 8 form no part of the claimed design where they appear as an indicator. The broken lines of the bottom of FIG. 5 form no part of the claimed design.

The present design is for a wing hand shaped display used for displaying various things, such as team names and/or logos, and is commonly worn over a person’s hand.

The bottom is in part plain and unornamented, and the unornamented portion is not claimed as part of the design.
